United States Patent Office.

DENISON CHAUNCY PIERCE, OF CLAYTON, NEW YORK.

Letters Patent No. 89,070, dated April 20, 1869.

IMPROVED RAILWAY-RAIL.

The Schedule referred to in these Letters Patent and making part of the same.

To all whom it may concern:

Be it known that I, DENISON CHAUNCY PIERCE, of Clayton, in the county of Jefferson, and State of New York, have invented new and useful Improvements in Railroad-Rails; and I do hereby declare the following to be a full, clear, and exact description of the nature, construction, and operation of the same, sufficient to enable others skilled in the art to which my invention appertains, to make and use the same, reference being had to the accompanying drawings, forming part of this specification, and in which—

Figure 1 represents a transverse vertical section of my improved railroad-rail; and

Figures 2 to 12, inclusive, are modifications of the same.

This invention relates to improvements in the compound railroad-rail, for which Letters Patent were granted to me, bearing date March 27, 1866, and numbered 53,479. In this patent, the rail is constructed in two parts, one of which constitutes the body, or main rail, and the other forms the cap, or head thereof, and serves as the table of the rail. Strips of prepared wood, or other suitable material, are placed between the cap and main rail, and all fastened together. By this arrangement the blows of the wheels of the passing trains are delivered upon the adjustable cap of the new rail, while it does not oppose a rigid resistance thereto, but yields to the extent of the material between it and the main rail.

The present invention has for its object to so construct the main rail as to utilize the material of which it is composed, and at the same time to so dispose the same as to afford the greatest possible lateral and vertical resistance to the strain incident to the passage over it of heavy-laden trains.

Similar letters of reference indicate corresponding parts in the several figures.

A represents the cap, composed of steel or iron, as shown in the patent hereinbefore referred to; and

B is the main rail.

In fig. 1, this rail is shown, formed with a downward-projecting flange, C, adapted to be let into the tie, for the purpose of holding it securely in place, at the same time permitting the lateral flanges D D, upon each side of the rail, to rest upon the ties, and afford a firm support for the tread, or cap.

The upper or vertical parts, E, of the main rail, are made hollow, having two flanges upon each side, in order to dispense with a large quantity of metal.

It is not necessary that this portion of the rail should be made solid, as the additional strength gained would be insufficient to compensate for the cost of the material.

I design to roll the main rail B in one piece, but, if found preferable, it may be rolled in two pieces, as indicated by the dotted lines in the flange C.

b b are strips of wood, or other elastic and suitable material, interposed between the cap and main rail, as before mentioned.

The portion of main rail between the flanges E E may also be filled with wood, but I prefer it to be of cement, being more economical.

Fig. 2, the main rail is composed of two pieces, B, with their upper sides lapped over each other, as shown at c. By this construction the rail is made hollow.

The main rail may also be made in two parts, with their upper and lower sides overlapping each other, as at c, fig. 3. In this figure the downward-projecting portion c is also made hollow.

Fig. 4 shows the rail made in two parts, joined together in the horizontal line x x.

In fig. 5, rail is made in one piece, open at the top b, and filled with wood or cement.

Fig. 6 is the converse of fig. 5, having the lower portion C open, and its top E closed.

Fig. 7 is the same as fig. 1, with the flange C removed.

In fig. 8, the parts C E are hollow, and open at the top and bottom, respectively. These parts are in the form of parallel flanges, crossing the lateral flanges D D at right angles, and extending equal distances from each side of the rail.

In the foregoing description, it will be seen that the form of rail, in all cases, embraces similar disposition of metal, and, furthermore, the greatest possible strength.

The whole rail may be fastened to the tie by bolts or screws, extending through the flanges of the cap and main rail, or by headed spikes upon each side of the flanges, in the usual manner.

Having thus described my invention,

I claim as new, and desire to secure by Letters Patent—

As an improvement upon my patent, granted March 27, 1866, No. 53,479, the construction of the main or base rail, when the same is provided with broad lateral flanges and a lower vertical flange, and when the central upper portion of the rail and lower vertical flange, either or both, are made hollow, and the rail is combined with a suitable cap and interposed strips, substantially as and for purposes set forth.

D. C. PIERCE.
